ATTORNEY

UNITED STATES PATENT OFFICE.

JOHN A REISER, OF PORT JERVIS, NEW YORK.

MEASURING CAP FOR BOTTLES.

Application filed January 22, 1928. Serial No. 82,921.

The device, the subject of this invention is a cap for bottles and I particularly refer to the type of cap usually applied over a cork or other sealing means.

5 The particular objects of the invention is to provide a cap that will have a use other than merely that of assisting in sealing or of protecting the closure of a bottle. The use that I particularly refer to is that of 10 serving as a dosage measurer or spoon.

I have found that it is difficult to instruct a patient or the public generally as to the exact amount of medicine to be taken, for the reason that 'one spoonful' is designated, 15 the spoon selected may be of any one of a number of different sizes. When spoons were made of but two standard sizes, the directions 'one teaspoonful' or 'one tablespoonful' had definite meaning, but with the great 20 number of spoons of different sizes now found in common use, such directions are practically meaningless.

It is my purpose, therefore, to provide a dosage measuring device having the second 25 function of a bottle closure and in this way make it possible to assure that each patient will receive exactly the same quantity of any given preparation.

Another object of the invention is to provide 30 means whereby and with no inconvenience, the dosage measuring device will be always available and this is particularly important for travellers or for those going from place to place and with my device 35 when the bottle is properly closed the dosage measuring device is associated with the bottle, to be removed therefrom only when desired for use.

With these objects in view the following 40 is what I consider the best means of carrying out my invention and the accompanying drawing should be referred to for a complete understanding of the specification which follows.

45 In the drawing:—

Fig. 1, shows in elevation, a bottle and in section, a closure thereover.

Fig. 2, shows a screw cap closure with an extension or foldable handle.

50 Fig. 3, shows a closure of large capacity, and

Fig. 4, shows a closure of a different type and having its extension so arranged as to serve with a seal.

Figure 5 is a perspective view of the cap 55 shown in Figure 1, reversed, showing its use as a dosage measurer.

Similar reference numerals indicate like parts in all the figures where they appear.

At 1, in Fig. 1 I show a bottle. The neck 60 of this bottle is formed with two diameters as are many similar bottles. The larger diameter 2 is 'ground'. The smaller diameter 3, formed as an extension from the larger portion 2 receives a cork 4. The cork 65 4 is retained in place by means of a closure cup or cap 5 and in this construction this closure cup or cap is formed of glass, the inner surface being 'ground' to a small extent to allow it to adhere closely to the 70 'ground' portion 2 of the bottle neck.

Formed integral with the cap 5 is an extended handle 6 and I call attention to the fact that this handle is so shaped as to allow it to lie closely upon the adjacent portion of 75 the bottle. This is important as it makes a compact package and assures that the handle will not be broken.

The cap 7 in Fig. 2 is of metal and may be an ordinary screw cap having screw 80 threads 8. Formed integral with or extending from the cap 7 is a metallic strip in two parts, 9 and 10, the parts being hinged together at 11 and one of the parts having an extending tongue 12, which will limit the 85 hinging movement. In this construction the handle members 9 and 10 may be of strip metal so that they may be bent to closely engage the bottle wherein the cap is arranged.

The cap 12, shown in Fig. 3 may be provided with flexible tongues 13 and 14 and should be provided with a handle 15, which is also a strip of metal. This cap may be used to enclose the nipple of a nursing 95 bottle and may be used as a cream dipper or for other desirable purposes.

The cap 16, shown in Fig. 4 is provided with an impressed portion 17 and a slotted band 18 which will allow the cap to be 100 snapped over a suitable projection or lip upon the bottle neck. The handle 18, a somewhat flexible metallic strip, will also be formed to follow the contour of the bottle, but in this arrangement I show a seal 105 20 upon the bottle and engaging the end of the handle so that the handle serves the double purpose of a handle for the cup or

cap 16 and a sealable member which will serve to doubly protect the contents of the bottle.

When in use as a dosage measurer or spoon, the position of any of the caps will be, obviously, reversed into that shown in Fig. 5 and this figure is inserted solely for the purpose of suggesting the second operative position of the measurer or cap.

10. While I have shown a number of common constructions of my device, I desire it understood that modifications may be made within the scope of the appended claim, without departing from the principle or sacrificing 15 the advantages of the invention.

Having carefully and fully described my invention, what I claim and desire to secure is:—

A dosage measuring device comprising a cap, screw threaded means for retaining it 20 over the mouth of a bottle and a closure therein and an extended handle formed integral with said measuring device, said handle being in two parts, hingedly connected and extending down the neck of the bottle. 25

Signed at the town of Port Jervis, county of Orange, State of New York, this 9th day of January, 1926.

JOHN A. REISER.
